(57) **CLAIM**

The ornamental design for a locking well cap, as shown and described.

DESCRIPTION

FIG. 1 is a perspective view of a locking well cap of the present design;

FIG. 2 is a top plan view of the locking well cap;

FIG. 3 is a side elevation view of the locking well cap;

FIG. 4 is a side elevation view of the locking well cap from the other side;

FIG. 5 is a front elevation view of the locking well cap;

FIG. 6 is a rear elevation view of the locking well cap;

FIG. 7 is a bottom plan view of the locking well cap;

FIG. 8 is a perspective view of the locking well cap attached to a well; and,

FIG. 9 is an exploded view of the locking well cap.

The broken line showing in FIG. 8 is included for the purpose of illustrating environmental structure and forms no part of the claimed design.
